UNITED STATES PATENT OFFICE.

JOSEPH KINSTLER, OF CHICAGO, ILLINOIS.

PACKING-BAG.

SPECIFICATION forming part of Letters Patent No. 662,000, dated November 20, 1900.

Application filed February 8, 1900. Serial No. 3,827. (No model.)

To all whom it may concern:

Be it known that I, JOSEPH KINSTLER, a citizen of the United States, residing at Chicago, in the county of Cook and State of Illinois, have 5 invented certain new and useful Improvements in Packing-Bags, of which the following is a specification.

The object of this invention is the production of a packing-bag especially adapted to 10 the needs of campers and sportsmen, a bag which is storm-tight, adjustable within certain limits to different amounts of luggage, and which is adapted to be carried in the hand or strapped upon the back like a knapsack. 15 In the accompanying drawings, Figure 1 is a front elevation of my improved packing-bag. Fig. 2 is an end view of the same. Fig. 3 is a front view showing the parts extended. Fig. 4 is a plan view showing the same partially folded. Fig. 5 is a front elevation showing the bag packed part full. Figs. 6, 7, and 20 8 show the manner of folding and closing the bag when it is only partially filled with luggage. Fig. 9 is an end view of the bag as shown in Fig. 5, and Fig. 10 is an enlarged detail showing the means of securing the parts together.

Like letters of reference indicate corresponding parts throughout the several views. 30 In the construction of this packing-bag I prefer to use a heavy waterproof canvas provided with a double hem at most of the seams and edges to give stiffness and strength. The body portion consists, essentially, of the front, bottom, and back of the bag and the top flap, which are in one piece, and the two ends secured by sewing or by other suitable means to the edges of said first-mentioned piece, which ends, being rectangular, give a rectangular form to the bag. Following this outline and referring to the drawings, A is the main piece composing the body portion of the bag, A' being the front, A² the front flap formed integral therewith, A³ the bottom, A⁴ the back, A⁵ the top flap, and A⁶ two pocket-flaps secured in suitable positions upon the side edges of the top flap. All the edges of the canvas piece A are double-hemmed except the curved forward edge of the top flap 45 A⁵ and the edges of the pocket-flaps A⁶, which edges are bound with leather.

B represents two end pieces of rectangular

form, the edges of which pieces are double-hemmed, like those of the main piece A, and stitched to the front, to the bottom, and to 55 the back A', A³, and A⁴, respectively, of said main piece. B' represents cover-flaps formed integral with the said end pieces B and having, like said end pieces, double-hemmed edges. 60

C represents handle-straps, one of which is secured to the front A' and the other at a point directly opposite on the back A⁴ of the bag. These handle-straps are secured by rivets, by stitches, or other suitable means of 65 fastening. C' represents buckles secured to the front and back of said bag at points directly opposite, which buckles are intended to receive the ends of the handle-straps C. The arrangement of the points of attachment of 70 the handle-straps C and the buckles C' to the front and back of the bag is such that the straps may be buckled into the buckle on the same side of the bag as its fastening, or each strap may be crossed over and buckled upon 75 the opposite side of the bag.

D represents binding-straps for entirely surrounding the bag.

D' represents the usual buckles, and D² loops for holding the straps in proper position 80 on the bag. These straps are free to slide within the loops D² and may be entirely withdrawn from the bag.

In use the desired quantity of clothing, &c., is packed within the bag, and if the quantity 85 is sufficient to fill the same the cover-flaps B are folded over upon the contents of the bag and the front flap A² folded upon said cover-flaps. The top flap A⁵ is now brought forward over the whole, the pocket-flaps A⁶ being folded outside to protect the joint between the ends and the top and to prevent rain from beating into the bag at this point. The straps D are secured about the bag and drawn tight. If the bag is to be carried in 90 the hand or between two persons, the handle-straps C are buckled, as shown in Figs. 1, 2, and 3; but if the load is intended to be carried on the back the handle-straps C are crossed and each buckled on the opposite side of the bag 95 from its point of attachment. The middle strap D may be left securely buckled about the bag; but the end straps may be loosened to permit the insertion of the arms of the person. 100

son, upon whose back the bag is to be borne, between said straps and the bag upon the rear side thereof. The bag is made smooth on its rear side, so that no projections will hurt the back of the person carrying it.

To fold the bag when only partially filled, the top flap A^5 is folded over upon itself, the front flap A^2 rolled inward with said top flap, and the back A^4 and the front A' also included in said roll. The cover-flaps B' and the pocket-flaps A^6 are not used when the bag is folded in this way, the former being turned inward against the inner face of the ends B and the latter against the inner side 15 of the top flap, as shown in Fig. 3. The straps D are buckled about the bag, as shown in Figs. 5 and 9, and the handle-straps C are adjusted to a proper length. The bag when thus folded is completely stormproof.

20 While I have described this bag as constructed of canvas, it is plain that leather or any other flexible material may be used.

I claim as my invention—

1. In a packing-bag, in combination, a single main piece composing the body portion 25 of the bag, and forming the front, the bottom, the back, the front flap, and the top flap thereof; end pieces of rectangular outline secured to the edges of the main piece, which 30 end pieces have cover-flaps formed integral therewith; pocket-flaps secured to the side edges of the top flap; binding-straps adapted to surround said bag; and handle-straps se-

cured to the sides of said bag at points directly opposite, and adapted to have an adjustable connection with said bag either on the same side to which they are fastened or on opposite sides thereof. 35

2. In a packing-bag, in combination, a single main piece composing the body portion 40 of the bag; end pieces secured to the edges of said main piece; and handle-straps secured at points substantially opposite on the opposite sides of said bag, which straps at their free ends are adapted to be detachably secured to said bag, either on the same side 45 with their attachment thereto, or on the opposite side thereof.

3. In a packing-bag, in combination, a single main piece composing the body portion 50 of the bag, and forming the front, the bottom, the back, the front flap, and the top flap thereof; end pieces of rectangular outline secured to the edges of the main piece; binding-straps extending about said bag parallel 55 with said main piece; and handle-straps secured at points substantially opposite on the opposite sides of said bag, which straps at their free ends are adapted to be detachably secured to said bag, either on the same side 60 with their attachment thereto, or on the opposite side thereof.

JOSEPH KINSTLER.
